UNITED STATES PATENT OFFICE.

FANNIE M. MANSFIELD, OF HAVERHILL, MASSACHUSETTS.

DESIGN FOR A TOY CAT.

Application filed January 5, 1928. Serial No. 24,755. Term of patent 7 years.

To all whom it may concern:

Be it known that I, FANNIE M. MANSFIELD, a citizen of the United States, residing at Haverhill, in the county of Essex and State of Massachusetts, have invented a new, original, and ornamental Design for Toy Cats, of which the following is a specification, reference being had to the accompanying drawing, forming part thereof, in which—

Fig. 1 is a front elevation of a toy cat showing my new design, and
Fig. 2 is an edge elevation thereof.

I claim:

The ornamental design for a toy cat as shown.

In testimony whereof I have signed my name to this specification.

FANNIE M. MANSFIELD.
